UNITED STATES PATENT OFFICE.

WILLIAM ANDREW SCHAUML, OF BALTIMORE, MARYLAND.

DESIGN FOR A BOTTLE-CAP-RESHAPING DIE.

SPECIFICATION forming part of Design No. 30,048, dated January 24, 1899.

Application filed November 5, 1898. Serial No. 695,625. Term of patent 14 years.

To all whom it may concern:

Be it known that I, WILLIAM ANDREW SCHAUML, a citizen of the United States, residing at Baltimore, in the State of Maryland, have invented and produced a new and original Design for Bottle-Cap-Reshaping Dies, of which the following is a specification.

The drawing illustrates two views of the punch part of a reshaping-die. This die has a flat circular face *d*, projecting downward from the center, and a flat ring-face *c*, surrounding said center, but on a different plane and adjoining the rim of the die-head. A curved fillet *e* extends around the said circu-

lar central face and between it and the ring-face. A stem *b* projects upward from the top side of the die-head.

Having described my design, what I claim is—

The design for a bottle-cap-reshaping die, as herein shown and described.

In testimony thereof I affix my signature in the presence of two witnesses.

WILLIAM ANDREW SCHAUML.

Witnesses:

CHARLES B. MANN, Jr.,
LEE I. VAN HORN.
